CLAIM

The ornamental design for a power drill with battery pack, as shown and described.

DESCRIPTION

FIG. 1 is a front perspective view of a power drill with battery pack showing my new design;

FIG. 2 is a side view thereof;

FIG. 3 is the opposite side view of FIG. 2 thereof;

FIG. 4 is a front view thereof;

FIG. 5 is a rear view thereof;

FIG. 6 is a top view thereof; and

FIG. 7 is a bottom view thereof.

FIG. 8 is a front perspective view of a first alternate embodiment of my new design;

FIG. 9 is a side view thereof;

FIG. 10 is the opposite side view of FIG. 9 thereof;

FIG. 11 is a front view thereof;

FIG. 12 is a rear view thereof;

FIG. 13 is a top view thereof; and

FIG. 14 is a bottom view thereof.

FIG. 15 is a second alternative embodiment of my new design;

FIG. 16 is a side view thereof;

FIG. 17 is the opposite side view of FIG. 16 thereof;

FIG. 18 is a front view thereof;

FIG. 19 is a rear view thereof;

FIG. 20 is a top view thereof; and,

FIG. 21 is a bottom view thereof.

The broken line showing of the word Bosch is included for the purposes of illustration and forms no part of the claimed design.
